UNITED STATES PATENT OFFICE.

JOHN H. GUNNISON, OF MADISON, WISCONSIN.

DRAG BUCKET.

Application filed January 23, 1926. Serial No. 83,220.

This invention relates to excavating apparatus and more particularly to an improved drag bucket or scraper.

An object of the present invention is the provision of a generally improved and simplified construction that may be economically produced.

Another object is the provision of a device which will have great strength and which will not require cross braces and the like.

Another object is the provision of the device having scraping edges along the top and bottom so that the device may be reversed and operated in either position.

Another object is to adapt the device for use in hard ground or the like by providing its scraping or excavating edges with sharpened blades or plow points.

Another object is to relieve the draft means or drag links, particularly adjacent their connection with the scraper or bucket of excessive wear in the operation of the device.

To acquaint those skilled in the art with the manner of constructing and practicing the present invention, I shall now describe a particular embodiment of the same in connection with the accompanying drawings, in which,

Figure 1 is a plan view of one embodiment of the invention;

Fig. 2 is a side elevation;

Fig. 3 is a transverse section, partially in elevation and taken on the line 3-3 of Figure 1;

Fig. 4 is a section taken on the line 4-4 of Figure 2; and

Fig. 5 is a section taken on the line 5-5 of Figure 1.

Referring to the drawings, the particular embodiment of the invention shown comprises a generally U-shaped body portion 5, which consists of a back wall 6 having side walls 7 and 8 extending forwardly therefrom and open at the front at 9. The body 5 is preferably cast as an integral unit of suitable wear resisting metal, such as cast steel, manganese steel or a suitable alloy, although this, of course, may vary as desired.

The forwardly extending side walls 7 and 8 may diverge slightly toward the open front 9. The upper and lower edges of the body 5 have integral flanges 15 and 16.

These flanges are preferably formed integral with the side walls 7 and 8, and they are rounded at 17, 18 and extend inwardly at 19, 20 generally normal to the side walls 7 and 8 and back wall 6. The flange 15 extends continuously about the upper edges of the walls 6, 7 and 8, from the front edge of the side wall 8. The flange 16 similarly extends continuously about the lower edges of the walls 6, 7 and 8 from the front edge of one side wall to the front edge of the other side wall. The upper and lower edges of the scoop or bucket are thereby identical so that the device may be reversed for scooping, excavating or scraping on either of said edges, as desired.

The flanges 15 and 16 increase in width along the side walls 7 and 8 from the front edges of said walls to the back 6, as shown at 20 in Figure 1. I find that this produces an exceptional reinforcement or strengthening along the upper and lower edges of the device, against contracting of the walls 7 and 8 and against any other distortion or stresses to which devices of this sort are subjected. With this strengthening or reinforcement, cross braces or the like between the opposite sides at the open front of the device may be eliminated, as shown. The flanges 15 and 16 perform the dual function or purpose of providing scraping edges along the top and bottom and at the same time they reinforce and strengthen the entire device. The two flanges work together to provide an exceptional overall reinforcing or strengthening and they make the top and bottom of the device alike or identical so that it may be reversed or used for excavating or scraping on either its upper or lower edges. The gradual widening of the flanges 15 and 16 at 20 provides exceptional strength at the base or back 6 and the corresponding diminishing in width or narrowing of said flanges toward the front ends of the walls 7 and 8 admirably adapts said flanges for cutting or digging ahead into the ground or other material, decreasing the resistance to the digging or cutting action toward the front edges which, of course, take into the material first.

The front ends of the flanges 15 and 16 terminate in forwardly projecting cutting blades or plow points 25 which are preferably formed integral with the body 5 and

which are preferably sharpened into relatively sharp cutting edges or blades 26 shown as disposed obliquely (Figure 3), and thickened at 27 for adequate strength.

- 5 The edges of the flanges 15 and 16 are preferably sharpened at 30 to provide relatively sharp cutting or digging edges within the bowl or body and entirely around the upper and lower flanges 15 and 16 thereof.
- 10 For the purpose of connecting or attaching the forward draft device to the bucket, the side walls 7 and 8 are provided internally with draft connections which may be in the form of eyes 40 or any other suitable or preferred formation, as desired. To the connections 40 are suitably attached the draft links shown in the form of chains 42 although this too may vary. The connection of the links 42 to the connections 40 may be 15 through suitable U-bolts, clips or otherwise as desired.

It will be apparent that the connections 40 and the attachments of the links 42 thereto are all disposed completely within the 20 side walls 7 and 8 and that said side walls 7 and 8 extend externally over the same and protect said connections 40 and the attachments of the links 42 thereto against excessive wear. As the device is moved over the 25 ground or other material, the connections 40 and attachment of the links 42 are kept out of wearing contact with the hard ground externally of the bucket or side walls 7 and 8.

30 The cutting blades or plow points 25 are disposed forwardly of the connections 40 and attachment of the links 42 thereto, and break and loosen the ground or other material excavated or scraped before the draft 35 connections and attachments are subjected to the material. The material is thereby loosened up and the wear on these connections on the inside is minimized. The wear on the outside is entirely eliminated.

40 The links 42 may be attached at 50 to a hauling chain or cable 52 or to any other suitable or preferred draft appliance, by which the scraper may be drawn forwardly. Four connecting links 42 may be employed

45 or two only may be employed and these may be connected to the top or bottom connections 40 according to the draft desired. Normally, with the scraper operating on one edge, these links may be attached to the bottom connections 40 and when the scraper is turned over or reversed for operation on its opposite edge, the attachment may be to the other pair of connections 40. Additional adjustment of these connections may be 50 provided for, as desired.

55 For the purpose of hauling the scraper rearwardly, the body 5 may have a plurality of suitable draft connections 60 which may also be conveniently in the form of eyes integral with the back wall 6. Draft

links for drawing the scraper rearwardly are shown at 62 and suitably attached to the connections 60 at 63.

60 From the foregoing, it will now be apparent that the device is simple and inexpensive. The bucket is easily made and the manufacturing and laboring costs are low. The device has effective scraping or digging action on its upper or lower side and may be reversed, as desired. The device has great strength and cross braces and the like are not necessary and the draft connections are protected against excessive wear.

65 The cutting edge on the front of each side wall of the bucket and its formation there, makes it possible to readily cut into a bank with a perpendicular or substantially perpendicular wall.

70 The bucket is adapted for stripping overburden mineral deposits and in doing this work the bucket may be continuously drawn laterally into the bank or sidewise into the bank, by means of sheaves arranged at the front and rear for the cables or other elements used to haul the buckets back and forth. In starting a stripping job a straight cut down to the mineral to be stripped is preferably made first, and then by moving the rear sheave the bucket may 75 be brought into the bank laterally and the sharpened ends of the side walls unhampered by the hauling cable attachments is drawn along, shaving into the bank and by holding the rear cable taut while the bucket 80 is being drawn forward the cutting into the bank is expeditiously brought about, and the bucket filled with this material from the sides of the bank rather than with the mineral or material being stripped under 85 or beneath the bucket. The disposition of the cable attachment inside the side walls and rearwardly of the cutting blades, not only protects these attachments against excessive wear, but eliminates any interference of said attachments with the cutting 90 action of said blades.

95 I do not intend to be limited to the precise details shown or described.

100 I claim:—

105 1. A scraper comprising side walls having a closed back and an open front, a pair of cutting and reinforcing flanges, one along the top and the other along the bottom of the scraper, and extending continuously 110 about the upper and lower edges respectively of the side and back walls to the outer ends of the side walls at the open front of the scraper and forming angular cutting blades, one at the top and one at the 115 bottom of the end of each of said side walls, said flanges extending laterally from said side and back walls substantially normal thereto, increasing in width from the open front to the closed back of the scraper and 120

125 said flanges extending laterally from said side and back walls substantially normal thereto, increasing in width from the open front to the closed back of the scraper and 130

projecting from the top and bottom of each side of the open front to provide projecting plow points with the side walls terminating short of said projecting points between the 5 top and bottom of the scraper.

2. A scraper comprising side walls having a closed back and an open front, a lateral cutting and reinforcing flange extending continuously about the upper edge of 10 the scraper and forming cutting blades at the upper edges of the outer ends of the side walls at the open front of the scraper, and a lateral cutting and reinforcing flange extending continuously about the lower edge 15 of the scraper and forming cutting blades at the lower edges of the outer ends of the side walls at the open front of the scraper, the forward ends of said side walls being centrally removed and terminating short of 20 said cutting blades.

3. A generally U-shaped scraper having a substantially vertical back wall and substantially vertical side walls extending substantially normal thereto and open at the front, 25 the intermediate portions of the forward edges of said side walls being removed and a pair of angular cutting blades at the forward ends of each of said side walls, one at the upper and the other at the lower edges 30 of said walls above and below said centrally removed portions.

4. A scraper comprising side walls having an open front and a back wall closing the back of the scraper, a lateral cutting and reinforcing flange extending continuously 35 about the back and side walls of the scraper and projecting beyond the side walls at the open front of the scraper and forming forwardly projecting cutting blades, the forward edges of said side walls terminating 40 short of said projecting cutting blades and draft connections on the inner sides of said side walls rearwardly of said projecting blades and disposed wholly between the side walls, said side walls extending externally 45 over said draft connections to enclose said connections wholly between said side walls and protect the draft connections against wear.

5. A reversible scraper having side walls 50 open at the front and flanged along the top and bottom, angular plow points at the top and bottom of the forward end of each side wall, said plow points projecting forwardly beyond the intermediate portion of the side 55 walls at the open front of the scraper and said intermediate side wall portions being centrally removed and terminating short of said projecting plow points.

In witness whereof, I hereunto subscribe 60 my name this 18th day of January, 1926.

JOHN H. GUNNISON.
